(57) **CLAIM**

The ornamental design for a plunger, as shown and described.

DESCRIPTION

FIG. 1 is a front perspective view of a plunger according to an embodiment of the present design; FIG. 2 is front elevation view of the plunger of FIG. 1; FIG. 3 is a rear elevation view of the plunger of FIG. 1; FIG. 4 is a left side view of the plunger of FIG. 1; FIG. 5 is a right side view of the plunger of FIG. 1; FIG. 6 is a top plan view of the plunger of FIG. 1; FIG. 7 is a bottom plan view of the plunger of FIG. 1; and, FIG. 8 is a rear perspective view of the plunger of FIG. 1. The broken lines in the drawings are for the purpose of illustrating portions of the plunger that form no part of the claimed design. The dot-dash lines in the drawings represent the bounds of the claimed design and form no part thereof.

1 Claim, 7 Drawing Sheets

Related U.S. Application Data

which is a continuation of application No. 14/204, 227, filed on Mar. 11, 2014, now Pat. No. 11,311,312.

(60) Provisional application No. 61/788,940, filed on Mar. 15, 2013.
